ULTRA HIGH FREQUENCY ELECTRON
DISCHARGE DEVICE SYSTEMRobert Sloss, Audubon, N. J., assignor to Radio
Corporation of America, a corporation of Dela-
ware

Application August 26, 1944, Serial No. 551,289

4 Claims. (Cl. 250—36)

1

The present invention has for its primary object to provide a frequency converter or mixer circuit suitable for use at very high frequencies of the order of 3000 megacycles.

Another object is to provide a compact, very high frequency converter system suitable for use in a radio relaying system adapted to receive angular velocity modulated waves and to convert these waves to waves of another frequency.

The frequency converter of the invention includes a concentric line resonator at whose high voltage end there is mounted a non-linear device in the form of a crystal detector bridging the space between the inner and outer conductors of the resonator. This detector is connected at one end to the outer conductor of the resonator and has its other end protrude into the interior of the hollow, inner conductor through an aperture in the inner conductor. The resonator is fed with waves of two different very high frequencies so as to cause the detector to produce a beat frequency equal to the difference frequency. Both waves develop voltage on the line resonator, and hence, voltage at both very high radio frequencies is developed across the terminals of the crystal rectifier.

A feature of the invention lies in the mounting of the local oscillator and its associated cavity resonator, as a result of which it is possible, by a simple adjustment, to move as an integral unit the entire oscillator assemblage including the output probe.

A description of the invention follows in conjunction with a drawing, wherein:

Fig. 1 schematically illustrates the frequency converter or mixer circuit of the invention, including the associated local beating oscillator;

Fig. 2 illustrates in detail the mechanical assemblage of the circuit elements of Fig. 1, particularly the local oscillator and frequency converter, and the manner in which the local oscillator unit can be moved by a simple adjustment, in accordance with the invention; and

Fig. 3 is a side view of the apparatus of Fig. 2 as seen looking in the direction of the arrow 3 with the oscillator removed.

Throughout the figures, the same or equivalent parts are given the same reference characters.

Although the present invention is hereinafter described with particular reference to a radio relaying system adapted to receive angular velocity modulated waves, it should be clearly understood that it is not limited thereto and has more general uses.

Referring to Fig. 1 in more detail, there is

2

shown a source of input waves of a mean frequency of 3000 megacycles in the form of a transmission line 700. This line may extend to a suitable receiving antenna (not shown), or any other source of waves. The energy of 3000 megacycles impressed upon the line 700 may be suitably modulated as to frequency, such that the input frequency varies plus and minus 1.17 megacycles, by way of example. Line 700 is provided with a surrounding metallic conducting shield 702 which is grounded at 704. The frequency converter or mixer comprises a metallic cavity resonator 706 which is preferably cylindrical in shape. This resonator has its external surface grounded at 704. Coupling between the cavity resonator 706 and the input line 700 is made by means of loop 705. In the alternative, line 700 may be replaced by a wave chute or guide.

Extending within the resonator 706 and connected to one of its bases is cylindrical line section 790 whose base 791 is adjacent and spaced from the metal circular base 792 carried by metal bellows 711. The line section 790 acts as an inductance and is tuned by means of this cylindrical metallic bellows 711 having, as indicated, springy corrugated side walls. By means of the bolt 713 and nut 715, the capacity between plates 791 and 792 is adjusted as is also the volume or internal cubical content of the resonator. Preferably the line section 790 is approximately one-quarter wave-length long—here about $\frac{3}{4}$ of one inch. This line section is tuned by adjustment of plate 792 to the frequency of the waves received and fed in at loop 705. A crystal detector 708 is mounted as shown at the high voltage end of the line section 790 with one terminal 795 in electrical contact with a wall of resonator 706 and its other terminal 796 protruding through opening 797 in the cylindrical line section 790. Terminal 796 is connected to conductor or line 710. As a result, the crystal detector rectifies the waves fed in at 705 and 718 and feeds the resulting difference frequency of about 30 megacycles into line 710.

The cavity resonator 706 is also supplied with high frequency oscillations by means of a capacity end plate 718 located in the interior of the cavity resonator and fixed to the inner conductor 720 of an exposed section of coaxial transmission line 722 which inner conductor extends into the resonator. The conductor 720 is excited by an automatic frequency controlled high frequency oscillator operating in the neighborhood of either 3030 megacycles or 2070 megacycles. The oscillator will be described more fully later.

The crystal detector 708 rectifies the waves fed in at 705 and 718 and produces a beat frequency of 30 megacycles which is fed through line 710 shielded by the surrounding conductor 712 to the primary coil 716 of a transformer whose secondary coil 726 is tuned by condenser 728. The output of the tuned circuit 726, 728 is fed through line 732 to the first stage of suitable intermediate frequency amplifiers and limiters.

The high frequency oscillator 738 operates in the neighborhood of 2070 megacycles or 3030 megacycles. The oscillator comprises an evacuated container 738, a cathode 734 grounded at 736, a negatively biased plate 756, a cavity resonator 742 charged with voltage of a positive polarity from battery 298, and a grid 744 connected to the resonator 742. The resonator 742 (shown in cross section) is cylindrical in shape and is made of metal. This resonator has end plates or bases 752, 754 which are perforated and to which are attached the hollow metallic inner tubular conductors 746, 750. The metallic tubes 746, 750 are separated at an intermediate point so as to provide a gap 748. Oscillations are set up in the cavity resonator 742 and wave output is derived from the inductive loop 740 coupled to the space within the cavity resonator 742. The external surface of the cavity resonator 742 is grounded at 724.

By properly choosing the dimensions of the cavity resonator 742 and by appropriate adjustment of the tube voltages, oscillations at a desired frequency may be had. By suitable external means (not shown) the shape of resonator 742 may be warped so as to change its cubical content and, hence, its frequency of operation. Or, if desired, a metallic bellows adjustment, such as that provided for the cavity resonator 706 may be provided for cavity resonator 742, but in this case, of course, the container 738 should be hermetically sealed to resonator 742 so that a portion of its external surface containing and otherwise supporting the metallic bellows structure would be exposed for external adjustment.

The output appearing in the tuned circuit 726, 728 would be, for the example chosen, a wave having a mean frequency of 30 megacycles and maximum frequency deviation of ± 1.17 megacycles. This wave is fed to suitable intermediate frequency amplifying, limiting and discriminator detector stages.

Figs. 2 and 3 show in greater detail a mechanical arrangement of apparatus which the oscillator 738 and mixing and detecting system 706 of Fig. 1 may take. Fig. 2 is a plan view of the oscillator 738 and the mixing and detecting apparatus 706, the latter being shown in cross section for a clearer understanding of the apparatus. Fig. 3 is a view of the apparatus of Fig. 2 seen looking in the direction of arrow 3 with the oscillator 738 removed.

In Fig. 2, oscillator tube 738 is of the 726A-B type manufactured by the Western Electric Company. Adjusting bolt or screw A700 is used for the purpose of adjusting the volume of the cavity resonator within the oscillator tube, and hence the frequency of operation.

By rotating bolt A702, bracket A704 may be moved vertically along the grounded metallic support A706 in order to control the position of the conductor 720 and capacity plate 718 within the cylindrical housing 706 of the cavity resonator. Movement of the bracket A704 will move the entire oscillator tube assemblage including oscillator tube 738 and its associated cavity resonator

and the capacity plate 718, as a result of which the space within cylinder 706 between line section 790 and the capacity plate will be varied.

Crystal detector 708 has its upper terminal connected to the lead 710 corresponding to the internal conductor 710 of Fig. 1. This connection is made by way of the spring contact A710 contacting the upper terminals of the crystal 708 and insulatingly supported upon the base of and passing through the metal cylinder 706. The lower terminal of the crystal 708 is in direct contact with the grounded cylinder 706.

As shown in Fig. 3, the antenna lead 700 within the external grounded conductor 702 is held within the split clamp A720 which is locked against the external conductor 702 by adjustment of the nut A722. It will be noted that the internal conductor 700 is looped at 705 and soldered or otherwise fixed to and connected directly to the external conductor 702. Hence by simply moving external conductor 702 to the right or to the left, as shown in Fig. 3, the antenna coupling may be adjusted. It will be noted that the antenna coupling loop 705 projects into cylinder 706 in a direction substantially at right angles to the position of the conductor 720, the latter of which establishes communication with the high frequency oscillator 738.

The discriminator detector is diagrammatically illustrated at 208 in Fig. 1 across the output terminals of which are connected resistors 782, 784, which, as will be explained more fully later, provide automatic frequency controlling voltages. These voltages may then be used to control the frequency of oscillator 738 so as to maintain the beat frequency waves within the pass band of intermediate frequency amplifying and limiting stages.

The frequency controlling circuit for the oscillator 738 from which the automatic frequency controlling voltages are derived, is illustrated schematically in Fig. 1 in connection with vacuum tube 760. More specifically, a source of voltage 765 is connected across the leads or terminals 776, 778, and these terminals are connected to a potentiometer 774. By properly adjusting the tap 772 on potentiometer 774, and by proper choice of values for other circuit elements, the current flow through, or the conductivity of tube 760, having the anode 762, grid 764, and the cathode 768, may be controlled so that the voltage applied through lead 758 upon the plate 756 is of a desired value, such as for example, 150 volts. As indicated, the plate circuit for tube 760 is returned to ground through a resistor 761 shunted by condenser 792a and through the ground connection 763 to the source of potential 765. It should, therefore, be clear that the automatic frequency controlling voltages appearing across resistors 782 and 784 will vary the current flow through the tube 760 and hence its effective resistance. Consequently, the voltage in lead 758 will vary in such a way as to control the oscillator in that direction which will bring the beat frequencies appearing in tuned circuit 726, 728 back to the desired intermediate frequency pass band of the IFA system.

The present invention has been used with satisfactory results in a radio relaying system in which double angle frequency or double frequency modulated waves are received and heterodyned down to some convenient intermediate frequency. This intermediate frequency was amplified and limited and subjected to a single frequency de-modulation. The demodulated waves correspond-

ed in angle frequency or phase deviation with the modulated common sub-carrier wave. This reproduced sub-carrier at the relaying point, employing the frequency converter of the invention, was then used to directly frequency modulate a new high frequency carrier having a value and frequency suitable for retransmittal. Such a relaying system was found effective in minimizing cross-modulation and distortion.

Various alteration and modifications of the present invention may become apparent to those skilled in the art and it is desirable that any and all such modifications and alterations be considered within the purview of the present invention except as limited by the hereinafter appended claims.

Having now described my invention what I claim is:

1. An ultra high frequency device including a hollow electrically closed metallic chamber adapted to have periodically repeating electromagnetic waves produced therein, a bracket mounted on the exterior of said chamber, an electron discharge device circuit assemblage supported from said bracket in spaced relation to said chamber, said assemblage including an electron discharge device, an energy coupling element carried by said assemblage and extending into the interior of said chamber through an aperture in said chamber, and means for adjusting the position of said assemblage and coupling element as an integral unit relative to said chamber.

2. An ultra high frequency device including a hollow electrically closed metallic chamber adapted to have periodically repeating electromagnetic waves produced therein, a bracket mounted on the exterior of said chamber, an electron discharge device circuit assemblage supported from said bracket in spaced relation to said chamber, said assemblage including an electron discharge device and hollow metallic resonator supported by said bracket, an energy coupling element carried by said assemblage and extending into the interior of said chamber through an aperture in said chamber, and means for adjusting the position on said bracket of said assemblage and coupling element as an integral unit relative to said chamber.

3. An ultra high frequency device including a hollow electrically closed metallic chamber adapted to have periodically repeating electromagnetic waves produced therein, a bracket mounted on the exterior of said chamber, an oscillator circuit assemblage supported from said bracket in spaced relation to said chamber, said assemblage including an electron discharge device and a frequency controlling metallic resonator, an energy coupling element carried by said assemblage and extending into the interior of said chamber through an aperture in said chamber, means on said assemblage for changing the operating frequency of said frequency controlling resonator, and means for adjusting the position of said assemblage and coupling element as an integral unit relative to said chamber.

4. An ultra high frequency device including a hollow electrically closed metallic chamber adapted to have periodically repeating electromagnetic waves produced therein, a bracket mounted on the exterior of said chamber, an oscillator circuit assemblage supported by said bracket in spaced relation to said chamber, said assemblage including an electron discharge device and a frequency controlling metallic resonator, an energy coupling probe carried by said assemblage and extending into the interior of said chamber through an aperture in said chamber, means on said assemblage for changing the operating frequency of said frequency controlling resonator, and a rotatable element carried on said bracket for adjusting the position of said assemblage and probe relative to said chamber, to thereby vary the coupling between said oscillator circuit and said chamber.

ROBERT SLOSS.
